US00D515057S

(12) **United States Design Patent** (10) Patent No.: **US D515,057 S**
Oe et al. (45) Date of Patent: **** Feb. 14, 2006**

(54) **CELL PHONE**

(75) Inventors: **Yutaka Oe**, Tokyo (JP); **Nobuyuki Enomoto**, Kyoto (JP); **Fuji Asada**, Kyoto (JP); **Shigetaka Kanai**, Kyoto (JP)

(73) Assignee: **Vodafone K.K.**, Tokyo (JP)

(**) Term: **14 Years**

(21) Appl. No.: **29/193,879**

(22) Filed: **Nov. 13, 2003**

(51) LOC (8) Cl. **14-03**

(52) U.S. Cl. **D14/138**

(58) Field of Classification Search **D14/137, D14/138, 147-148, 247-248, 144, 341-347; 379/433.01-433.13, 434; 455/550.1-90.3, 455/575.3, 566, 575.1; D21/517; 345/169; 348/373-376; D16/208**

See application file for complete search history.

(57) **CLAIM**

The ornamental design for a cell phone, as shown and described.

DESCRIPTION

FIG. 1 is a front view depicting our ornamental design when closed;

FIG. 2 is a rear view thereof;

FIG. 3 is a right side view thereof;

FIG. 4 is a left side view thereof;

FIG. 5 is a top plan view thereof;

FIG. 6 is a bottom plan view thereof;

FIG. 7 is a front view depicting our ornamental design when opened;

FIG. 8 is a rear view when opened;

FIG. 9 is a right side view when opened;

FIG. 10 is a left side view when opened;

FIG. 11 is a top plan view when opened; and,

FIG. 12 is a bottom plan view when opened.

The broken line showings of portions of the cell phone throughout the views are for illustrative purposes only and form no part of the claimed design.
